UNITED STATES PATENT OFFICE

ARNOLD J. DECKER, OF WYANDOTTE, MICHIGAN, ASSIGNOR TO ALL-METAL PRODUCTS COMPANY, OF WYANDOTTE, MICHIGAN, A CORPORATION OF DELAWARE

AIR GUN

Application filed March 9, 1929. Serial No. 345,623.

This invention relates to an air gun and it has to do especially with an air gun in the nature of a child's gun or toy gun, which is of the repeating type.

5 The air gun of the present invention is one which embodies improvements over the one shown in the patent application of Victor H. Forsman, Arnold J. Decker, and Arthur W. Edwards, Serial No. 324,880, and filed December 10, 1928. The present invention embodies a mechanism for effecting the repeating action of the gun substantially as shown in this said application, but in conjunction with the mechanism there are a number of improvements both in details of the mechanism itself and in a safety apparatus which is effective during the cocking of the gun. The safety apparatus is such as to insure that the cocking action and the feeding of a pellet from the 20 magazine, both occur in a given cocking movement; in other words, the safety is provided so that it is not possible to perform either the feeding of the pellet or the cocking of the gun without effecting the other action. 25 This safety arrangement is also arranged to prevent accidental firing of the gun until the cocking action is entirely completed.

In the accompanying drawings:

Fig. 1 is a side view of a gun constructed 30 in accordance with the invention, with a portion of the stock cut away and with some of the parts in section illustrating the pellet feeding arrangement.

Fig. 2 is an enlarged sectional view, also 35 with some of the parts cut away, illustrating the safety mechanism and showing the same in uncocked position.

Fig. 3 is a similar view showing the position 40 of the parts during the cocking movement, but before the gun has been entirely cocked.

Fig. 4 is also a similar sectional view, illustrating the parts in cocked position, but before the pump handle has been returned to 45 its normal position.

Fig. 5 is a section taken on line 5—5 of Fig. 2, illustrating the parts forming the pump grip and also the connection therewith on the safety device.

50 Fig. 6 is a section taken on line 6—6 of

Fig. 2, illustrating the mounting of a safety pawl.

Fig. 7 is taken on line 7—7 of Fig. 4, in further illustration of the structural features of the safety mechanism.

55 Fig. 8 is a view of the underside of the barrel construction of the gun with the casing removed, however, in illustration of the arrangement of the safety mechanism.

Fig. 9 is a perspective view of a member 60 of the safety mechanism.

Fig. 10 is a perspective view of the feed member for feeding the pellets from the magazine to the barrel.

Fig. 11 is a detailed view illustrating the 65 trigger and sear.

The gun comprises essentially the usual barrel 1, stock 2, trigger 3, and pump handle 4. The pump handle may be carried by a sheet metal frame construction 5, generally 70 U-shaped in cross section, as illustrated in Fig. 5, and which engages the sides of the gun barrel and gun frame 6 in a manner to guide the handle 4 as it is reciprocated for cocking purposes.

75 The interior of the gun includes a mechanism which comprises a spring pressed plunger in the barrel which may be of any conventional construction. Such a plunger is shown at 10, mounted upon a rod 11 and 80 the spring is shown at 12. The plunger is disposed within a barrel 13, disposed with the barrel 1, and in this regard, the barrel 1 is in effect a false barrel. The rod 11 has a hooked end 12a which is arranged to be 85 caught behind a sear 14 on the trigger. The trigger being held normally with the sear urged upwardly by a suitable spring 15. Both the false barrel and the inner air barrel are slotted, as shown in Fig. 5; and attached 90 to the rod 11 is a depending member 16 which projects through the slotted barrels and which is connected to the pump handle 4. This may be accomplished by turning over 95 the ends 17 of the metal member 16 so as to effect the pump handle 4 to the part 16. The rod 11 is provided with an enlargement 18, forward of which is a sleeve 19 which spaces the enlargement 18 in the member 16. Accordingly, as will be noted 100

by reference to Figs. 2, 3 and 4, a backward pull on the handle 4 retracts the rod 11 until it is hooked behind the sear 14 of the trigger where it is held in its position. When the 5 trigger is pulled in the usual manner, the rod is released and the plunger moves forwardly in the barrel 13 under the action of spring 12.

The pellet to be ejected when the gun is shot is of course, disposed in the end of the 10 barrel 13, and the gun includes a magazine from which a pellet is fed in each cocking movement and placed in this position. The magazine is shown at 20 and it is provided with a spring-pressed follower 21, in the 15 nature of a cylinder with a crossed end 22 and a projecting handle 23. The pellets are shown at 24. To place the pellets in the magazine, the handle 23 is retracted beyond the opening 25 and then a plurality of pellets 20 are dropped in the magazine 20; and upon release of handle 23, they are urged forwardly by spring 26. The forwardmost pellet, however, is stopped because it butts against the end of a combined stop and feed 25 member 30. This member is shown in Fig. 10, and is advantageously composed of sheet metal bent generally into U-shape in cross section, provided with elongated apertures 32 and ears 33. The forward portion of the 30 magazine is cut away, or slotted as at 34, and the stop member 30 is mounted in place by means of a fulcrum pin 35 extending through the elongated slots. A suitable spring 36 is placed around the pin, preferably within 35 the member 30, one end of which engages an abutment 37 and the other of which engages the inner wall of the bight portion of the member 30. This spring holds the member 30 normally in position, shown in the full 40 lines of Fig. 1, with ears 33 abutting against the outside of the magazine and with the opposite end of the member 30 being urged upwardly so that the bottom of the elongated slots stop against the fulcrum pin 35. In 45 this position, the forwardmost ball, or pellet in the magazine strikes against the stop member. There is a slotted stop member which is fixed in position, as illustrated at 40, the purpose of which will presently appear.

50 This combined stop and feed member 30 is actuated when the gun is cocked to allow the forwardmost pellet to be forced out of the magazine by the spring 26 and then to feed this pellet upwardly into an approximate alignment with the barrel 13 so that it may be placed in the barrel. For accomplishing this, a gun is provided with a slot 40, having a lower substantially horizontal portion and upward substantially horizontal portion 55 and intermediate inclined portion. There is a U-shaped wire-like member 41 having its ends connected, as at 42 to opposite sides of the slide member 5, with its legs extending forwardly and with its bight portion 43 disposed in the slot 40.

This construction functions to feed a pellet from the magazine into the barrel 13 as follows: Upon retracting the member 4, the wire member 41 is also retracted, and the bight portion 43 strikes the end of the member 30 above the fulcrum pin 35; continued movement causes the bight portion to rock the member 30 to the position shown substantially by the dotted lines (Fig. 1). The forwardmost pellet now is moved forward owing to the action of spring 26 until it strikes the abutment 30; further continued retracting movement of the handle 4 causes the bight portion 43 of the wire to move past the engaged end of member 30, whereupon the spring 36 snaps the member 30 back to its normal position. This action moves the forwardmost pellet upwardly into the barrel 1, just forward of the barrel 13. Further retracting movement causes the bight portion 43 of the wire to ride upwardly in the inclined portion of the slot and eventually, into the upper horizontal portion where it engages the said pellet and forcefully urges it into the barrel 13, as shown by the dotted lines. The pump handle 4 is now pushed forwardly to its normal position and in so doing, the bight portion 43 must pass the member 30 which lies in its way. This is permitted because the member 30, by being engaged by the portion 43, moves downwardly due to the elongated slots moving down, as regards the fulcrum pin 35. In this movement, the member 30 fulcrums on the ears 33 and when the portion 43 clears the member 30, the same is urged back into its normal position by the spring. In other words, the spring 36 functions to permit the member 30 to be flexed downwardly at either end.

It will become apparent that the cocking of the gun, or in other words, the engagement of end 12 of the rod behind the sear 14 of the trigger must be accomplished at the time the pellet is fed into the end of the barrel 13, in order to effect perfect operation of the gun. The safety mechanism now to be described, is arranged to positively effect both the cocking and the feeding of the pellet in a given stroke or movement of the cocking handle 4.

By reference first to Fig. 9, there will be seen a member which contacts directly with the trigger. This member has a pair of relatively long strip parts 50 with a cross abutment 51. The ends of the parts 50 are pivoted as at 52 to an actuating member 53 which may be of U-shaped sheet metal having a bight portion 54. The member 53 is mounted in the gun upon a pivot 55.

Secured in an operative manner to the reciprocating handle is a member for cooperation with the pivoted actuating member 53. This member is referenced 60 and may be of channel formation and apertured to permit the member 16 to pass therethrough (Fig. 5), and secured to the member 16 by a suitable 120

pin 61. This channel extends rearwardly and normally terminates just forward of the actuating member 53.

Pivots secured on a fixed pivot, that is, fixed as regards the body of the gun, is a pawl 62 being mounted on pivot 63, and it is normally held substantially perpendicularly to the gun barrel by a spring 64. The member 60 is provided with a plurality of apertures 65 for cooperation with this pawl, and these apertures function as a rack, as will later be set forth. Also the member 60 has a relatively large aperture 66 and a similar relatively large aperture 67.

15 In considering the action of this mechanism, turning first to Fig. 2, where the parts are shown in normally uncocked position. The pawl 62 extends downwardly through the aperture 67. The operator now grasps pump handle and retracts the same, and after some retracting movement, the parts take the position substantially as shown in Fig. 3. Note the pawl 62 catches in the small aperture 65 in a manner as to prevent a reverse movement. Should the operator now release the pump handle, the parts do not return to the normal position, but remain held by the pawl. Continued retraction of the pump handle brings the parts to the position shown in Fig. 4, where the hook 12 catches behind the sear 14 on the trigger to cock the gun. At this time the bight portion 43 of the feeding wire has pushed a pellet into the end of the barrel 13.

35 The next move is to return the pump handle by a forward push to its normal position. It will now be noted that the pawl 62 under the action of its controlling spring 64, extends through the aperture 66 so that it is in its normal vertical position. The handle can now be pushed forwardly and the pawl will snap along in the apertures 65 in a position just reverse to that shown in Fig. 3, preventing, however, any return movement until the pump handle has been pushed to its forwardmost position in order to allow the pawl to again assume the position shown in Fig. 2. Accordingly, this pawl works as a check both in the retracting of the pump handle and in the forward return movement of the pump handle, and insures that both the retracting movement and the forward return movement be a full and complete stroke.

In addition to this check action performed by the pawl, the trigger is locked from movement in all positions of the pump handle, except in its forward normal position. Turning again to Fig. 2 where the parts are in normal position, it will be noted that upon retracting the pump handle the member 60 engages the bight portion 54 of the actuating member 53 and swings it upon its pivotal mounting 55 to the position shown in Fig. 3. This draws the members 50 forward so that the part 51 abuts up against the trigger, as

shown in Fig. 3, so that the trigger cannot be pulled. The trigger is thus held locked at the time of cocking (Fig. 4), and remains so held until the pump handle is returned to its normal position, thus causing the member 60 to move out from under the actuating member 53. The frame of the gun may be provided with an aperture 70 to afford clearance for the end of the actuating member 53 when it is cocked to the position shown in Fig. 75 2. The gun may now be fired by a pull upon the trigger, which movement may also retract the member 50 and rock the actuating member 53 from the position as shown in Fig. 4 to that shown in Fig. 2.

80 It will be understood that inasmuch as the trigger is held from movement, some movement must be provided in order to get the hook 12a over the sear 14, and for this purpose the trigger 3 and the sear 14 are made separate (Fig. 11). The trigger may be of bifurcated construction with the sear disposed therein, and the pin 3a upon which the trigger is fulcrumed may also fulcrum the sear on the trigger. A spring 15 normally holds the sear in the position shown in Fig. 11, up against a stop pin 3b, and as the hook 12 strikes the sear, the sear is cammed down thereby, as illustrated by the dotted lines of Fig. 11, against the action of the spring 15 95 90 However, as the trigger 3 is pulled by the finger of the operator, the sear 14 reciprocates therewith due to the abutment pin 3b.

Claims:

1. A repeating gun comprising in combination, a barrel, ejecting mechanism, cocking mechanism, means for feeding a shot to a position relative to the barrel to be ejected, manually operable means for cocking the gun and for feeding the shot, and reversible check means associated with the manually operable means arranged to insure complete movement of the said operable means once said movement is started and to check reverse movement thereof until a complete cocking movement has been effected.

- feeding a shot to a position as regards the barrel to be ejected, cocking means for the ejecting means, a reciprocable manually operable member effective to cause cocking of the gun and the feeding of a shot, a rack device associated with the reciprocable member, and a reversible pawl associated with a rack device for controlling the movement of the reciprocable member. 70
- 10 4. A repeating gun comprising in combination, a barrel, ejecting means, means for feeding a shot to a position as regards the barrel to be ejected, cocking means for the ejecting means, a reciprocable manually operable member effective to cause cocking of the gun and the feeding of a shot, a rack device associated with the reciprocable member, and a pawl associated with a rack device for controlling the movement of the reciprocable member, said pawl being adapted to reverse as regards the rack upon completion of said reciprocable motion and cooperate with the rack to control the reverse reciprocable motion. 80
- 15 5. In a gun, a trigger, spring controlled ejecting means, means for retracting the ejecting means against the action of the spring to catch the same on the trigger, a rack device movable with the ejecting means, and an automatically reversible pawl engageable with this rack device for controlling the movement of the ejecting means in such a way as to prevent reverse movement thereof prior to the completion of its retraction. 85
- 20 6. In a gun, a trigger, spring controlled ejecting means, means for retracting the ejecting means against the action of the spring to catch the same on the trigger, a rack device movable with the ejecting means, said rack device having a clearance space adjacent each end, a pawl normally lying in one of the clearance spaces, said pawl being arranged to catch on the rack during the retracting movement of the rack incident to cocking the gun, said pawl being adapted to swing into the clearance spaces at the opposite end of the rack whereby to reverse in position so as to function with the rack device to permit reverse movement of the rack and act as a check therefor in such movement. 100
- 25 7. In a gun, cocking means comprising a reciprocable rack member, a single pawl arranged therefor having a checking action on the rack in its reciprocable motions in opposite directions, said rack having clearance spaces near its ends to permit reverse of position of the pawl by permitting the pawl to swing into such clearance spaces. 115
- 30 8. In a repeating air gun, the combination of a barrel, spring controlled ejecting means, a trigger, a pump handle for cocking the ejecting means, means associated with the pump handle for feeding a pellet into the barrel as the pump handle is actuated, and rack and pawl check mechanism associated with 120
- 35 the pump handle arranged to positively require full stroke movements of the pump handle as it is actuated, said rack and pawl mechanism comprising a single rack and a single pawl, said rack having clearance spaces near each end and into which the pawl swings and reverses in position at the ends of the stroke movement of the pump handle. 125
9. In an air gun, the combination of a barrel, a spring pressed ejecting means therein, a trigger, a pivoted sear, a pump handle for retracting the ejecting means to catch the same on the sear, a locking abutment for the trigger, a pivoted actuating member connected to the abutment, means having a plane surface connected for movement with the pump handle positioned so that said pivoted member intersects its line of movement whereby said member swings the pivoted member as it moves thereunder to in turn move the abutment against the trigger to lock the same against movement. 130
10. In an air gun, the combination of a barrel, a spring pressed ejecting means therein, a trigger, a pivoted sear, a pump handle for retracting the ejecting means to catch the same on the sear, a locking abutment for the trigger, a pivoted actuating member connected to the abutment, means having a plane surface connected for movement with the pump handle positioned so that said pivoted member intersects its line of movement whereby said member swings the pivoted member as it moves thereunder to in turn move the abutment against the trigger to lock the same against movement, said plane surface being of such a length as to be effective throughout the entire cocking and return movement of the pump handle and ineffective only at the position of rest of the pump handle whereby the trigger is at all times locked during movement of the pump handle. 135
- In testimony whereof I affix my signature.
ARNOLD J. DECKER. 140
